CONTAINER END ASSEMBLING MACHINE

Ronald E. J. Nordquist, Maplewood, N. J., and
 Herbert F. Cox, Jr., New York, N. Y., assignors
 to American Can Company, New York, N. Y.,
 a corporation of New Jersey

Application March 12, 1946, Serial No. 653,776

3 Claims. (Cl. 93—55.1)

1

The present invention relates to container end assembling machines and the like and has particular reference to curling over a flange part of a fibre container body to hold an end member in place in the body. This is an improvement on the can end assembling machine disclosed in United States Patent 2,265,188, issued December 9, 1941, to J. H. Murch.

In securing end members to fibre containers of the character disclosed in United States Patent 2,085,979, issued July 6, 1937, to J. M. Hothersall, wherein a flange part of the can body is folded inwardly over the inserted end member, it has been found most convenient to fold the flange part with a curling head which travels in endwise relation to the end of the container to be closed. In such a curling head the curling edge sometimes cuts into the edge of the flange at the beginning of the curling operation and thereby splits the fibre material of which the body is made or crushes the flange so that difficulty is experienced in forming the end seam on the container. This is particularly true where the inherent spring in the body side walls bows or curves them outwardly beyond their normal straight, flat condition.

The instant invention contemplates overcoming this difficulty by providing a curling head having air blast nozzles for projecting blasts of air against the outer surface of the annular flange of the container body thus pressing and holding the flange inwardly toward the container end member prior to and during the curling operation.

An object of the invention is the provision of a mechanism for curling the flange of a fibre container body into overlapping relation to an end member inserted within the body, wherein fluid means are utilized for pressing and holding the annular flange of the body inwardly toward the container end member so that the flange will be properly engaged by the curling head and the edge of the flange will not be cut or crushed at the beginning of the curling operation.

Another object is the provision of such a curling head mechanism, wherein the pressing and holding of the annular flange of the body inwardly toward the container end member is effected by air blast nozzles controlled by valves actuated in time with the operation of the curling head so that improved curling action may be obtained.

Numerous other objects and advantages of the invention will be apparent as it is better understood from the following description, which, taken in connection with the accompanying drawings, discloses a preferred embodiment thereof.

Referring to the drawings:

2

Figure 1 is a sectional view of a curling head mechanism embodying the instant invention, the view showing one end of a container in place in the mechanism, with parts broken away;

5 Fig. 2 is a front or face view of the curling head of the mechanism shown in Fig. 1; and

Fig. 3 is an enlarged fragmentary sectional detail showing some of the parts in Fig. 1 in a different position relative to the container.

10 As a preferred embodiment of the instant invention the drawings illustrate principal parts of the container flange curling mechanism disclosed in the above mentioned Murch patent.

In such a mechanism the work to be done is 15 disclosed as a rectangular shaped square cross section fibre container body A (Fig. 1) having an inwardly bent annular bead or shoulder B which terminates in a straight longitudinally extending annular flange C. Bodies of this character when they enter the curling mechanism carry flat fibre end members D which are in inserted position within the container body and are in engagement with the bead shoulder B, as shown in Fig. 1.

25 A container body A with its inserted end member D is inserted endwise into the curling mechanism in any suitable manner, for example as disclosed in the above mentioned Murch patent. In this inserted position the end of the body is 30 surrounded by a container holding head 12 which carries a plurality of radially movable slides 17. There are preferably four of these slides, one located adjacent each side of the rectangular container body. These slides have movement

35 in slideways 18 formed in the holding head 12. At their inner ends the slides are formed with shaped jaws 19 which are adapted to engage within the bead shoulders B of the container body A (see Fig. 1). When moved into operative 40 position the jaws 19 grip the container on all sides and hold it firmly against displacement.

The container body A thus held against movement is disposed in endwise alignment with a curling head which includes a punch 21 which is 45 movable toward the adjacent held end of the container body. The forward end of the punch 21 preferably is hollow and is of such a shape as to provide a shell of square cross section to fit the square container body A. The face of 50 the punch shell is formed with a concave annular or peripheral recess 22 having a curved surface 23.

A flange confining ring member 35 is carried on the outside of the punch and is adapted to 55 slide on a shouldered section thereof. This ring

is square in cross section and is attached yieldably to the punch by long screws 36 each screw extending through a shouldered bore 37 in the ring. The screws are threaded into a shoulder portion 38 of the punch 21. A large head 39 is formed on each screw and these heads limit the inner travel of the ring. Compression springs 41 retained in bores 42, 43 formed respectively in the ring and in the punch shoulder, normally keep the ring in its inward position against the heads of the screws.

The innermost edge of the ring 35 extends beyond the punch 21 and is tapered both inwardly and outwardly to form a wedge 49. The inward taper, indicated by the numeral 51 is adjacent the container body flange C. The dimension between opposite inner faces of this ring adjacent the tapered surfaces 51 is exactly the dimension across the container on the outside of the flange C. Thus, the inner peripheral surface or contour of ring 35 and the outer peripheral surface or contour of punch 21 on which the ring slides are substantially coincident in outline with the perimeter or contour of the container body flange when the latter is straight. This straight condition of the container body flange will be referred to hereinafter as the "normal outer contour" of the flange.

The outer taper, indicated by the numeral 53, extends back to the outside of the ring. The 30 tapered wedge thus formed by these two tapered surfaces is adapted to extend into corresponding tapered recesses 55 formed in the jaws 19. These latter serve as centering devices for bringing the jaws into proper position, transversely of the container body when the punch moves forward.

Adjacent the wedge shaped edge of the square flange ring 35, a plurality of air blast nozzles 61 are located each for projecting compressed air or other fluid medium against the flange C of the container body. The function of this is for bowing and holding the flange inwardly toward the end member D during the curling operation. There are four of these nozzles 61, located one adjacent each face of the square ring 35. These nozzles extend inwardly at an angle toward the flange of the container body and are located in clearance openings 62 formed in the wedge shaped edge of the ring.

The outer ends of the nozzles 61 are connected to valve housings 64 (Figs. 1 and 2) secured to the outer face of the container holding head 12. There are four of these valve housings, one for each nozzle. The nozzle of each housing communicates with the outer end of an L-shaped channel 65 formed in the housing. The inner end of the channel communicates with a valve port 66 in the housing. The port is normally closed by a ball valve 67 located in an associated air chamber 68 formed in the housing. A compression spring 69 located in each chamber engages against the corresponding ball valve and exerts a pressure thereon to maintain it in valve closing position.

The air chambers 68 of all the valve housings 64 are maintained under air pressure by a pipe line 71 (Fig. 2) which connects all of the housings and is in communication with all of the air chambers. This pipe line 71 is connected to an inlet pipe 72 which leads from any suitable source of compressed air or other fluid medium.

Opening and closing of the valves is effected by actuating pins 73 which are slidably carried in the outer end of the valve housings. The in-

ner ends of the pins are disposed adjacent the ball valves 67. The outer ends of the pins extend beyond the housings and terminate adjacent the inner face of a plate 74 secured to the outer end of the punch 21.

Hence as the punch 21 moves toward the end of the held container body A for the curling operation, the plate 74 moves with the punch and thus comes into engagement with the outer ends of the pins 73 and simultaneously pushes all of the pins inwardly against the ball valves 67. This movement of the pins forces the ball valves inwardly away from the valve ports 66 and thus permits compressed air from the chambers 68 to flow through the channels 65 and the nozzles 61. This air issues from the nozzles in blasts which impinge against the outer surfaces of the four sides of the flange C of the container body and thus forces the sides of the flange inwardly from an outwardly bowed condition into a straight or slightly inwardly bowed condition. This stream of air against the flange along each of the four sides of the body continues during the entire inward travel of the punch and holds the flange in the desired position during at least the beginning of the curling operation.

As the punch 21 continues to move toward the end of the held container body A, the tapered wedge 49 surrounds the flange C while it is still maintained under the pressure of the stream of air projected against it and guides the flange into the ring. While the punch continues to move in toward the container body the wedge 49 of the ring engages into the wedge recesses 55 in the jaws 19 and thus properly centers them and the container held by them. This arrests further forward movement of the ring which remains stationary while the compression springs 41 yield to permit the punch to continue on its forward stroke.

The continued forward movement of the punch brings the curved surface 23 of the curling recess 22 into complete endwise engagement with the inwardly bent edges of the flange C held in this position by the air impinging against them. This insures that only the smooth curved surface 23 of the recess is presented to the flange and thus the curling action on the flange is immediately started and splitting or crushing of the flange is thereby prevented.

The curling action continues as the punch further proceeds toward the container body, the body flange sliding along the curling surface 23 of the punch until it is folded entirely over and is in overlapping position against the end member D. It is pressed home so as to crease the outer edge of the flange, as shown in Fig. 3.

The punch is thereupon withdrawn and the jaws are moved outwardly away from the container so that it may be removed from the head 12. During this outward movement of the punch, the plate 74 moves back away from the valve actuating pins 73 and thus permits the valve compression springs 69 to close the ball valves 67 against the air outlet ports 66. The streams of air issuing from the nozzles 61 are thereby cut off.

It is thought that the invention and many of its attendant advantages will be understood from the foregoing description, and it will be apparent that various changes may be made in the form, construction and arrangement of the parts without departing from the spirit and scope of the invention or sacrificing all of its material

advantages, the form hereinbefore described being merely a preferred embodiment thereof.

We claim:

1. In an apparatus for securing an end member in inserted position against a shoulder provided by an inwardly extending bead formed adjacent a projecting flange of a fibre container body, the combination of means engageable with said shoulder to hold the container in supported position, a movable die member disposed in spaced longitudinal relation to the supported body for engaging and bending inwardly the projecting flange of said body into overlapping position against the end member while said shoulder of the body is backed up by said holding means, said die member having an unbroken continuous working surface for engaging the full outer surface of said container body flange, means disposed adjacent the end of the container body for projecting a fluid medium against the body flange, and valve means engageable by said die member for actuating said fluid projecting means to impinge said fluid medium against said flange of the container body to press the flange inwardly into the path of travel of the moving die member to facilitate the aforesaid bending engagement of the die with the flange for securing the end member to the container body.

2. In an apparatus for securing an end member in inserted position against a shoulder provided by an inwardly extending peripheral bead formed adjacent a projecting peripheral flange of a fibre container body, the combination of a plurality of radially movable slide members for externally engaging said shoulder to hold the container in supported position, a movable die member disposed in spaced longitudinal relation to the supported body for engaging and bending inwardly the projecting flange of said body into overlapping position against the end member while said shoulder of the body is backed up by said slide members, said die member having an unbroken continuous working surface for engaging the full outer surface of said container body flange, a series of nozzles arranged around the end of the container body for projecting blasts of air against the body flange of the container, and valve means engageable by said die member for actuating said air blast projecting means to impinge said air blasts against periph-

erally spaced portions of said container body flange to press the flange inwardly into the path of travel of the moving die member to facilitate the aforesaid bending engagement of the die with the body flange for securing the end member to the container body.

3. In an apparatus for securing an end member in inserted position against a shoulder provided by an inwardly extending peripheral bead formed adjacent a projecting peripheral flange of a fibre container body, the combination of a plurality of radially movable slide members for externally engaging said shoulder to hold the container in supported position, a movable die member having means for supporting the same in spaced longitudinal relation to the supported body for engaging and bending inwardly the projecting flange of said body into overlapping position against the end member while said shoulder of the body is backed up by said slide members, said die member having an unbroken continuous working surface for engaging the full outer surface of said container body flange, a series of nozzles arranged around the supported end of the container body for projecting spaced air blasts against the container body flange, ports for connecting said nozzles with a source of compressed air, each of said ports including a valve seat normally closed by a valve member, and movable means actuated by the movement of said die member for opening said valve members prior to engagement of the die member with said container body flange, whereby a series of air blasts from said nozzles impinge against peripherally spaced portions of said body flange to press the flange inwardly into the path of travel of the moving die member to facilitate the aforesaid bending engagement of the die with the flange for securing the end member to the container body.
